UNITED STATES PATENT OFFICE.

JOHN LINDSAY, OF LURGAN, IRELAND, ASSIGNOR OF ONE-THIRD TO WILLIAM HENRY EVANS BROWN AND ONE-THIRD TO JAMES BELL, BOTH OF LURGAN, IRELAND.

THREAD-CUTTING AND THREAD-END-HOLDING DEVICE FOR EMBROIDERY SEWING-MACHINES.

1,373,747.

Specification of Letters Patent.

Patented Apr. 5, 1921.

Application filed May 13, 1918. Serial No. 234,279.

To all whom it may concern:

Be it known that I, JOHN LINDSAY, of Queen street, Lurgan, Ireland, a subject of the King of Great Britain and Ireland, have 5 invented certain new and useful Improvements Relating to Thread-Cutting and Thread-End-Holding Devices for Embroidery Sewing-Machines, of which the following is a specification.

- 10 This invention relates to sewing machines and it has for its object to provide improved means for cutting the threads above and below the material on which the sewing operation is being done, the cutting of 15 the thread being effected when the sewing operation has been completed at one part and it is desired to commence another sewing operation at a different place on the article being sewn.
- 20 The invention is particularly applicable to machine sewn embroidery, and like work, in which, at present, when one figure or portion of a pattern or design has been 25 sewn, the upper and under threads are drawn along with the article on which the 30 sewing is being done, to the point at which the next sewing operation is to be commenced, and, so on, until the pattern or design has been completed, the portions of 35 the thread between the various figures of the design having to be subsequently cut away. This invention obviates such subsequent cutting away or clipping, of the threads, thereby saving the cost of this operation and also saving the thread.

Under my invention the thread cutting means for embroidery and the like sewing machines is characterized by the cutting of the upper and under threads being effected 40 by cutting mechanism which is brought into action on the completion of any particular sewing operation and is provided with safety locking means whereby the cutting mechanism can only be operated when the 45 sewing needle is free of the cloth and also characterized by the mechanism for cutting the upper thread being caused to seize the thread above the cutting point and to hold same after the cutting operation and until 50 several stitches have been made by the sewing mechanism whereby the cut thread is prevented from being drawn out of the eye of the needle by the take up mechanism, means being also provided to draw off the

under thread ahead of the cutting operation in order to insure a sufficiency of thread below the cutting blade to take up the starting stitches of the next sewing operation. 55

In order that the invention may be clearly understood I have hereunto appended explanatory drawings, whereon, by way of illustration of example, the invention is shown applied to a Wheeler and Wilson sewing machine adapted for embroidery work. 60

Figure 1 is a back elevation of the sewing machine with my improvements applied thereto with the upper portion of the needle bar and appertaining parts broken off and shown separately in Fig. 1^a. 70

Fig. 2 is a cross sectional elevation on the line *x*, *x*, Fig. 1 and looking in the direction of the arrow *y*.

Fig. 3 is an elevation looking on the driving end of the machine with the driving 75 pulley removed to more clearly show the locking devices.

Fig. 4 is a detail plan view of the upper thread cutting shears and showing them in the "out of action" position. 80

Fig. 4^a is a perspective view of the cutting shears in the out of action position as shown in Fig. 4.

Fig. 5 is a detail view corresponding to Fig. 4 but showing the cutting shears in 85 the position which they occupy after cutting the upper thread.

Figs. 6 and 6^a are detail views of the throat plate and cutting blade for cutting the under thread. 90

Referring to the drawings:—

In carrying out the invention, as shown in the drawings, I provide a lever member 1 pivotally carried on the frame 2 of the machine, being connected therewith at the 95 pivot point 3. The end 1^a of the lever 1 is connected with a vertically slidable bar 4 connected with a foot treadle or equivalent (not shown) whereby the end 1^a of the lever 1 can be pulled down against the action of a spring 5. A downward movement of the lever end 1^a causes its end 1^b (shown broken off) to be correspondingly raised. The end 1^b of the lever 1 is connected with the presser foot lifting mechanism, being engaged in a slot in a vertically slidable bar 6 which connects with the presser bar 7 in such manner that the raising of the bar 6 100 105

by the end 1^b of the lever 1 will effect a raising of the presser foot bar and so raise the presser feet of the machine. The raising of the end 1^b of the lever 1 also presses 5 back the cam-shaped end 8^a (see also Fig. 2) of a lever 8 pivotally connected, at 8^b, with the machine head 9. This lever 8 is made, at its other end 8^c, with a slot 8^d which, when the end 8^a is pressed backward, as 10 above described, is caused to come into the path of movement of a spring catch 10 provided at the top of the needle bar 11. The needle bar 11 has a sleeve 11^a surrounding it and connected directly with the 15 needle operating mechanism, and the needle bar 11 can be connected with and disconnected from this sleeve 11^a by means of the spring clutch or catch 10 which has a hook 10^a adapted to engage a projection 11^b at 20 the top of the needle bar sleeve 11^a. While the machine is sewing, the hook 10^a of the spring catch 10 remains in engagement with the projection 11^b on the needle bar sleeve and so effects the reciprocation of the needle 25 bar 11 and needle 12. When, however, the lever 1 is operated for the purpose of actuating the cutting mechanism as hereinafter described, it is necessary that the needle should be held up clear of the cloth. For 30 this purpose the catch 10 comes into operation to disconnect the needle bar 11 from its operating sleeve 11^a by the raising of the end 1^b of the lever 1, causing a forward movement of the end 8^c of the lever 8 35 whereby the slot 8^d therein is caused to engage the backwardly projecting portion 10^b of the catch 10 so that the catch 10, and the needle bar 11 connected therewith, are prevented from descending while the 40 sleeve 11^a continues in action during the thread cutting operation. Connected with the lever 8, at 8^c, is an end 13^a of another lever 13 which is pivotally connected with the machine head at 13^b and has its other 45 end 13^c connected with the upper end 14^a of a member 14 which, at its lower end 14^b, carries the upper thread cutting shears. The member 14 is turnably supported on a bracket 15 projecting from the bar 7 which 50 carries the presser feet 7^a and 7^b and, at the lower end 14^b, the member 14 has a plate 14^c pivotally connected to it and to which the cutting shears 15^a and 15^b (Figs. 4 4^a and 5) are pivotally connected. The cutting 55 shears 15^a and 15^b extend forward on each side of the presser foot bar 7 and needle 12. When the shears 15^a and 15^b are moved back, by the raising of the front end 1^b of the lever 1, to the position 60 immediately above the needle hole in the throat plate, the cutting members 15^c and 15^d of the shears are also moved toward one another from the position shown at Figs. 4 and 4^a to the position shown at Fig. 5 this 65 movement being obtained from a bar 16

which passes through the presser bar 7 and has, at its lower end, arms 16^a and 16^b carrying pins 16^c and 16^d which engage in slots 15^e and 15^f in the shear members 15^a and 15^b. The upper end of the bar 16 is cranked, as shown at Fig. 2 and the cranked end 16^e is connected by a link 17 with a member 18 pivotally connected with the lever 1 at 18^b and projecting above the lever 1 and having a slot or opening 18^a therein. When the 70 bar 16 is turned to effect the cutting of the thread, the portion 15^g of the cutting member 15^c pushes the thread under the cutting edge α and draws off a certain amount into the jaws of the cutting member 15^d (Fig. 4^a) 75 and after the cutting operation has taken place by the meeting of the cutting edges α , α' , the upper thread is held between the members 15^c, 15^d above the cutting point so long as the shearing members 15^a and 15^b 80 remain in the position shown at Fig. 5. Immediately after the cutting operation the shears 15^a and 15^b close with the upper thread held between the meeting edges of the cutting members 15^c and 15^d to prevent 85 the take up drawing the thread out of the eye of the needle, until a number of stitches have been made by the sewing mechanism. This holding of the upper thread is effected by a catch 19 which is pivotally connected 90 at 19^a with the plate 20 and has, at its end 19^b, a projecting pin 19^c. This pin 19^c is capable of being engaged in the opening 18^a of the member 18 on the lever 1 and, when it is in engagement therewith, the 95 shears 15^a and 15^b are closed, with the members 15^c and 15^d holding the upper thread. The opening 18^a in the member 18 allows the latter to move in the direction of the arrow ε (Fig. 1) under the action of a 100 spring 21. This movement of the member 18 effects a corresponding movement of the link 17 and cranked bar 16 whereby the pins 16^c and 16^d are turned in such manner as to close the shearing members 15^a and 110 15^b and so cause the portion 15^g to coöperate with the cutting member 15^d to hold the upper thread so long as the pin 19^c remains in the opening 18^a. In order to hold the upper thread, after the cutting operation, 115 and to release it when the predetermined number of stitches have been sewn, a slidably supported ratchet member 22 is provided having slots 22^a and 22^b engaging pins 19^a and 19^c on the catch 19. When the machine is running and the cutting device is not in action the pin 19^c of the catch 19 will be in the position shown at Fig. 1 and the ratchet member 22 will be out of engagement with the pawls 23 and 24; when, 120 however, the cutting mechanism has been operated and the end 1^a of the lever 1 has been lowered so that the pin 19^c engages in the opening 18^a in the member 18, the raising of the lever end 1^a will bring the 125 130

teeth of the ratchet member 22 into engagement with the pawls 23 and 24. This upward movement of the member 19 is effected against the action of a spring 26. 5 The pawl 23 is connected with the stud 25 of the cross over cam and the usual oscillation of the stud 25 causes the pawl 23 to move the ratchet member 22 toward the member 18 by a step-by-step movement, corresponding to the number of stitches required to be made before the release of the upper thread from the shearing members and, in completing this movement, the ratchet member 22 will tilt over the member 18 until the pin 19^e is clear of the opening 18^a whereupon the spring 26 will pull down the member 19 to the position shown at Fig. 1 and the re-action of the spring on the member 18 will cause same to open the shear members 20 15^c and 15^d so as to release the thread. During the forward movement of the ratchet member 22 the pawl 24 holds the ratchet member and prevents it moving back when the pawl 23 is lifted at each oscillation of 25 the stud 25. The ratchet member 22 moves forward against the action of a spring 27 which re-acts to pull back the ratchet member 22 when the pin 19 has dropped clear of the opening 18^a as above described. 30 In order to prevent the possibility of the cutting mechanism being operated, when the needle is in the cloth, I provide an automatic locking device as shown at Figs. 1 and 3. This locking device consists of a cam 35 member 28 secured on the machine shaft 29 and adapted to act on a locking member 30 having a portion 30^a which normally projects under a portion 1^d at the end 1^a of the lever 1 so as to lock same except at such 40 times as the cam 28 moves the locking member 30 clear of the part 1^d of the lever 1. The cam 28 is arranged to move the lever member 30 clear of the part 1^d when the take up is at its highest point with the 45 needle clear of the cloth. I also provide a locking lever 31 which has a portion 31^a normally under the projecting part 1^d of the lever 1 so as to prevent the operating of the lever 1 and cutting mechanism but 50 which, by a pull on its end 31^b, can be moved by the operator so as to be clear of the part 1^d of the lever 1 in order to allow of the cutting mechanism being operated when required. The end 31^b of the locking lever 55 31 would be connected to a suitable operating treadle or equivalent. A spring 32 keeps the locking member 30 in contact with the cam 28 and a spring 31^c keeps the locking lever 31 normally in the locked position. 60 The under thread is cut simultaneously with the upper thread, or slightly later, by means of a cutting blade 33 which co-operates with a cutting edge or cutting portion 34^a on the underside of the throat plate 34. 65 This cutting blade 33 is actuated by the

downward movement of the sliding bar 4 connected at its lower end 4^a, with a lever 35 on the end 36^a of a shaft 36, which, at its other end 36^b, has a crank 36^c connected with a bar 37 having the under cutting 70 blade 33 secured at its end 37^a. The cutting blade 33 is made with a cutting edge 33^b and an extension 33^c which at each cutting operation is adapted to push the thread ahead of the cutting edge 33^b and to draw 75 off sufficient thread below the shearing point to provide a sufficiency of under thread for the starting stitches at the next sewing operation.

Although I have described the cutting 80 mechanism as operated by the foot it may be operated by hand or by the knee.

Having now fully described my invention what I claim and desire to secure by Letters Patent is:—

1. In or for sewing machines for doing embroidery or like work on cloth, cutting mechanism for cutting the upper and lower sewing threads, means connected with the pressure bar of the machine, for operating 90 said upper thread cutting mechanism, means for operating said under thread cutting mechanism, and a pivotal catch and sliding member whereby the upper thread, after being cut, is held and prevented from 95 being drawn out of the eye of the machine needle until several stitches have been made by the machine.

2. Thread sewing devices for embroidery sewing machines comprising a lever pivoted 100 to the head of the machine, a lever connected with the first mentioned lever and connected with another lever supported by the pressure bar of the machine, a plate on the last mentioned lever, a pair of horizontally disposed levers pivotally supported on the plate, thread cutting and holding devices for the upper thread carried by the horizontally disposed levers and means whereby the operation of the levers to effect the cutting of the thread is prevented except when the needle of the machine is clear of the cloth.

3. In or for sewing machines for doing embroidery or like work on cloth, cutting 115 mechanism for cutting the upper and lower sewing threads comprising upper cutting blades, means for operating same, an under cutting blade, means for operating same, means preventing the blades operating when 120 the needle is in the cloth and an extension on the under cutting blade for drawing off a sufficiency of thread for the starting stitches of the next sewing operation.

In testimony whereof I affix my signature 125 in presence of two witnesses.

JOHN LINDSAY.
